UNITED STATES PATENT OFFICE.

CHARLES WILLIAM OAKES AND EDGAR BOYD CAMP, OF BILLINGS, MONTANA TERRITORY.

HOT-AIR FURNACE.

SPECIFICATION forming part of Letters Patent No. 321,632, dated July 7, 1885.

Application filed June 12, 1884. (No model.)

To all whom it may concern:

Be it known that we, CHARLES WILLIAM OAKES and EDGAR B. CAMP, of Billings, in the county of Yellowstone and Territory of 5 Montana, have invented a new and Improved Hot-Air Furnace, of which the following is a full, clear, and exact description.

Reference is to be had to the accompanying drawings, forming a part of this specification, 10 in which similar letters of reference indicate corresponding parts in all the figures.

Figure 1 is a sectional side elevation of our new and improved furnace, taken on the line $x x$ of Fig. 3. Fig. 2 is a sectional plan view, 15 taken on the line $y y$ of Fig. 3, and Fig. 3 is a front elevation of the furnace.

The invention will first be described in connection with the drawings, and then pointed out in the claim.

20 Referring to the drawings, A represents the outer casing of the furnace, closed at its ends by the end walls, B B'.

Within the outer casing, A, is placed the smaller casing C, closed at its ends by the 25 said end wall, B, and the opposite inner wall, C', which latter, with the outer wall, B', forms the hot-air space D, which communicates with the surrounding hot-air space E, formed by the inner and outer casings, A C.

30 The space G inclosed by the inner casing, C, bottom F, and the said end walls, B C', is the fire box or chamber of the furnace, which is connected to the chimney by the pipe H.

In the fire-chamber G are placed, above the 35 center thereof, the horizontal air-heating drums or cylinders J J, and series of vertical or nearly vertical air inlet and heating pipes K, which connect the heating-cylinders J with the external air through suitable openings 40 made through the bottom F. The heating drums J communicate with the hot-air space D through suitable openings made in the inner wall, C', as shown clearly in Fig. 1.

45 L are the grate-bars of the furnace, below which is formed the ash-pit M, and N N are the pipes for conducting the heated air from the surrounding air-space E to suitable distributing-pipes leading to different parts of the building.

50 In the front wall, B, above the heating-drums

J, is formed the opening O, closed by a suitable cap, so that by removing the cap the drums J may be cleaned of any soot or ashes that may collect upon them, and below the opening O is formed in the front wall B the 55 door P, through which the fuel may be introduced into the furnace upon the grate-bars L.

It will be noticed that the grate-bars L are located between the series of vertical air-inlet pipes K, and that the said series of pipes converge toward each other so as to stand partially over the grate-bars at their upper ends, leaving considerable space between the outer surfaces of the pipes and the inner surfaces of the inner casing, C, thus furnishing space for 60 the fire to circulate freely among and around the pipes K, and causing at the same time the flame to spread and nearly encompass the drums J. In this manner a large and very effective heating-surface is furnished within the 65 fire-box G without materially interfering with the draft of the furnace, and the inner casing, C, and end wall, C', furnish another very large and effective heating-surface for the air, so that all of the available heat from the furnace 70 will be taken up by the air and distributed through the building, making the furnace very economical in fuel.

Having thus described our invention, we claim as new and desire to secure by Letters 75 Patent—

The hot-air furnace herein described, the same consisting, essentially, in outer casing, A, having end walls, B B', the inner casing, C, having a rear end wall, C', between which 80 and the end wall B' an air-space, D, is formed, the air-space E between the top and sides of the said casings, the fire-box G, formed by the interior of the casing C, the two horizontal drums J in the upper part of casing C, the series of vertical inclined pipes K, extending 85 from the drums J to openings in the bottom F, and the grate L in the space between the drums and pipes K, substantially as set forth.

CHAS. WILLIAM OAKES.
EDGAR BOYD CAMP.
